Primary Examiner — Selina Sikder*(74) Attorney, Agent, or Firm* — Burr & Brown(57) **CLAIM**

The ornamental design for wafer holding member, as shown and described.

DESCRIPTION

FIG. 1 is front perspective view of a wafer holding member illustrating our new design;

FIG. 2 is a top plan view thereof;

FIG. 3 is a bottom view thereof;

FIG. 4 is a front view thereof, the rear view being a mirror image;

FIG. 5 is a left side view thereof;

FIG. 6 is a right side view thereof;

FIG. 7 is a sectional view taken along line 7-7 of FIG. 2;

FIG. 8 is an enlarged view of portion 8 encircled in FIG. 7; and,

FIG. 9 is a perspective view of wafer holding members in use. The broken lines are shown for illustrative purposes only and form no part of the claimed design.
